UNITED STATES PATENT OFFICE.

HENRY RUEGG, JR., OF WEEHAWKEN, NEW JERSEY.

PILE FABRIC.

Application filed January 12, 1923. Serial No. 612,304.

To all whom it may concern:

Be it known that I, HENRY RUEGG, Jr., a citizen of the United States, and a resident of Weehawken (Kingswoods), in the county of Hudson and State of New Jersey, have invented a new and Improved Pile Fabric, of which the following is a full, clear, and exact description.

This invention relates to fabric and particularly to what is known as pile fabric and has for an object to provide an improved construction wherein the pile is cut and the cut parts held in an efficient manner.

Another object of the invention is to provide a pile fabric for rugs and other articles using the pile fabric wherein comparatively short piling is provided and at the same time an effective structure presented whereby the piling is firmly held in the desired position.

20 In the accompanying drawing—

Figure 1 is a plan view of a fabric in a distended or stretched condition showing how the same is woven with a cut pile thread.

25 Figure 2 is a plan view of the cloth shown in Figure 1 with the pile cut and the fabric contracted in one direction.

30 Figure 3 is an edge view of part of the structure shown in Figure 2 illustrating how the ends of the pile thread extend upwardly to produce the desired pile effect.

In providing a pile fabric according to the present invention, a regular woven fabric is utilized consisting of the usual warp threads 1 and weft threads 2. As indicated in Figure 1, there is woven into the fabric a pile thread 3 in a well known manner so that the thread will pass over a weft thread under a warp thread and then over a second weft thread on the opposite side of the 35 warp thread. It will thus be noted that the pile thread is alternately on opposite sides of its companion warp thread and continually resting on top of the various weft threads so that when it is cut according to the present invention a very effective holding structure is produced as indicated more particularly in Figures 2 and 3.

40 From the bottom portion of Figure 1, it will be seen that according to the present invention the lowermost pile thread 3 is cut at points 4 while the next thread is cut at points 5 which is half way between points 4. The third pile thread from the bottom is 45 cut in line with points 4. The next pile thread 3 is cut opposite the points 5 and so

on for the full width of the fabric. The showing in Figure 1 is very much distended while the showing in Figure 2 is distended longitudinally somewhat to illustrate the appearance of the pile after it has been cut. As 60 clearly indicated in Figures 2 and 3, the various sections of the pile thread are provided with two upstanding legs or sections 6 and these legs extend downwardly and under one of the warp threads 1 and then 65 over a weft thread. As the weft threads are forced into close proximity in the finished fabric, the upstanding legs 6 of one section will press against the upstanding legs of 70 the next section so that the various sections coact to hold each other in place and to make effective the holding structure produced by the way each section is looped. This construction and arrangement is such that if one of the legs 6 is pulled upwardly 75 with the intention of removing that particular section of pile thread, sufficient friction will usually be provided by the way the parts are looped as to prevent the removal of the pile. For instance, if one of the 80 legs 6 is pulled upwardly, the strain will be around the lower half of the weft thread and then over the upper half of the warp thread and finally over the lower half of the same weft thread. This change of direction of the thread produces such a friction that usually the legs 6 would be pulled in half or broken before that part of the pile fabric would be removed. It will thus be 85 seen that the pile is by a simple holding structure, held firmly in place and, consequently, will present an extremely desirable 90 finished article.

What I claim is:—

95 A pile fabric, comprising a fabric body having warp and weft threads and a pile thread for each warp thread, said pile threads being arranged in pairs and passing over each second weft thread at adjacent 100 points and intermediate weft threads at spaced points with two warp threads therebetween, said pile threads being severed at each alternate weft thread, one pile thread being severed adjacent one weft thread and the next pile thread being severed at the 105 next weft thread so that the point of severing of the respective pile threads will be offset.

HENRY RUEGG, JR.
